UNITED STATES PATENT OFFICE.

DONALD NOBLE, OF BRIDGEPORT, CONNECTICUT, ASSIGNOR TO THE SINGER
MANUFACTURING COMPANY, A CORPORATION OF NEW JERSEY.

CRANK HEMSTITCH-EMBROIDERING MACHINE.

1,058,892.

Specification of Letters Patent.

Patented Apr. 15, 1913.

Application filed November 27, 1909. Serial No. 530,141.

To all whom it may concern:

Be it known that I, DONALD NOBLE, a subject of the King of Great Britain, residing at Bridgeport, in the county of Fairfield 5 and State of Connecticut, have invented certain new and useful Improvements in Crank Hemstitch-Embroidering Machines, of which the following is a specification, reference being had therein to the accompanying 10 drawings.

This invention relates to improvements in what are commercially termed crank hemstitch embroidery machines, wherein the material is fed in different directions by 15 means of feeding mechanism operatively connected with a manually controlled crank which is mounted so that it may be conveniently manipulated.

In the operation of machines of the character herein referred to, it is desirable when 20 directing a seam at an angle to the one previously formed to suspend the forward feed of the material while manually adjusting said material to its position for the commencement of the newly directed seam; and if, as is herein pointed out, the machine is 25 brought to rest between the successive hemstitch figures, stitches will be placed in a circular form between the last feed movement 30 of the finished seam and the first feed movement of the seam next to be made.

The invention is herein shown and described in connection with so much of a crank hemstitch embroidery machine as is 35 deemed necessary for an understanding of its practical application.

For details in construction of the variety 40 of machine shown in connection with the present invention see U. S. Patent No. 1,033,055, dated July 16, 1912, to D. Noble.

Referring to the accompanying drawings, in the several figures of which like parts are 45 similarly designated, Figure 1 is a view in front side elevation of the improved mechanism, together with so much of the embroidery machine as is deemed essential for an understanding of the invention, certain of the elements being shown in section and others in full lies for convenience of 50 reference. Fig. 2 is a rear side elevation of Fig. 1, except that a portion of the stop-motion mechanism has been removed to better illustrate the operative relationship of the latter and the means for suspending the

forward feed of the material between the successive hemstitch figures. Fig. 3 is an enlarged view of the stop-motion plunger and the connections for connecting it with its operating cam. Fig. 4 is a detail perspective view, partially in section, of the feed lever and parts carried thereby. Figs. 5 and 6 are views of the front and rear faces, respectively, of the feed cam, the latter figure including the gear for connecting said cam with the crank or main shaft of the embroidery machine. Fig. 7 is a rear side face view of the cam provided with the cam section for controlling the movements of the stop motion plunger, said cam being mounted at the rear of and upon the same shaft as the feed cam.

1 is the bed plate of the sewing machine, 2 the overhanging arm, 3 the arm standard, 4 the hand crank for controlling the direction of the feed of the material, and 5 the 75 commonly employed rotating cylinder provided with the vertically movable feed ring 6 which, at predetermined intervals, acts upon the beveled portion 7 of the rock lever 8 to advance the material in a given line of 80 feed, as in the device of the previously referred to application.

9 represents the feed cam which is provided with the cam groove 10 having the cam section 11, said cam being secured upon 85 the rotary shaft 12 which, in turn, is mounted in suitable bearings formed in the overhanging arm and operatively connected with the actuating mechanism of the sewing machine to make one rotation to every three 90 rotations of the main or crank shaft 13, as is necessary in forming the hemstitch figure.

14 is a shaft mounted to rock in suitable bearings formed in the overhanging arm, and upon the forward end of said shaft is 95 mounted the feed cam lever 15 constructed with a boss 16 in which is loosely mounted a roller stud 17 provided at its inner end with a roller 18. The roller 18, except as later pointed out, tracks the cam groove 10 100 and is normally held in operative relationship with said cam groove by a spring 19. 20 is the feed ring lever secured by pinch screw 21 upon the hub 22 of the lever 15, said hub being provided with a slot 23 so 105 as to permit the pinch screw 21 to tighten it upon the shaft 14 when adjusted to secure the lever 20. The outer end of the lever 20

carries a roller stud 24 upon which is mounted a roller 25 (shown in dotted lines only) which enters a groove 26 formed in the feed ring 6, thus causing said ring to act upon the lever 8 whenever the roller 18 is acted upon by the cam section 11 of the cam groove 10.

The stop-motion mechanism herein employed is of ordinary construction, comprising the means shown and described in the previously referred to pending application; and is substantially the same as the stop mechanism represented by United States patent to D. Nobile No. 656,853, dated August 28, 1900, accordingly, only such reference will be made thereto as is deemed necessary to show its control of the means for suspending the action of the machine between the successive hemstitch figures.

20 The shaft 12 carries at its rear end a cam disk 27 and is operatively connected, through the gear 28 carried by the cam 9 meshing with the gear 29, with the crank shaft 13, said gears being of the ratio of three to one and thus transmitting one rotation to the cams 9 and 27 to three rotations of said crank shaft.

To prevent the operator from arresting the action of the stitch-forming mechanism except at the completion of the hemstitch figure, the cam disk 27 is provided with a cam portion 30 which coacts with a roller 31 mounted upon the free end of a connection 32 which is pivoted to oscillate on the screw 33, the opposite end of said connection being jointed to an L-shaped lever 34 pivoted at 35 to a bracket 36 which, in turn, is secured by screws 37, 37 to the arm standard.

40 The L-shaped lever 34 is pivoted to a plunger 38 which is mounted in a suitable bearing formed in the arm standard, the free end of said plunger normally extending out slightly beyond said standard.

45 39 is a spring, one end of which is attached to the overhanging arm, the opposite end being secured to the connection 32, thus holding the free end of the plunger 38 in its outward position except when the roller 31 is acted upon by the cam portion 30, at which time the free end of said plunger is drawn within its bearing.

40 represents the hand or band wheel which is loosely mounted upon the crank shaft 13, 41 the brake disk suitably secured to said shaft, and 42 and 43 the commonly employed coacting toothed disks for releasing the band wheel from driving relationship with the shaft 13 whenever it is desired 55 to arrest the action of the machine. The disk 43 is provided with an arm 44 which is pivotally connected with a brake lever 45. The lever 45 carries at its lower end a follower 46 which tracks in a groove 47 formed 60 in the shipper lever 48 pivoted by screw

49 to the arm standard, a brake shoe 50 secured by screw 51 being carried by said lever at its opposite end.

The toothed disk 42 has formed integral with it a downwardly extended arm 52, the lower end of which is pivotally connected with a threaded bolt 53 which passes loosely through a bracket 54 secured to the arm standard, a spring 55 being located between the arm 52 and said bracket to yieldingly hold the disk 42 against partial rotation when acted upon by the disk 43.

The lever 48 has formed integral with it a stop lever 56 which, in connection with the plunger 38, acts to prevent the stop-motion mechanism from arresting the action of the machine except at the completion of a hemstitch figure, as will later be explained.

57 is a spring secured at one end to the arm standard, its opposite end being attached to the lever 48, said spring, through the connections previously pointed out, acting to hold the brake shoe 50 in contact with the cam portion 57' formed on the periphery of the brake disk 41. Such adjustment of the parts 48 and 50 causes the follower 46 to be positioned in the lower end of the slot 47 and the free end of the lever 56 to be advanced past the free end of the plunger 38.

In the operation of the stop-motion mechanism, supposing the machine to be at rest, the operator by manipulating a suitably connected treadle (not shown) rocks the lever 48 in opposition to the spring 57, 100 which positions the follower 46 in the upper end of the slot 47, the brake shoe 50 out of engagement with the brake disk 41, the lever 56 with its free end below the plunger 38 and the well understood driving elements 105 into operative relationship for effecting transmission of power from the belt driven pulley to the crank or main shaft 13. When it is desired to reverse the action of the stop-motion mechanism to stop the machine, the operator permits the spring 57 to control the rocking movements of the lever 48 which causes the latter to position the end of the lever 56 in contact with the plunger 38, where it is held until the connection 32, 110 through the action of the cam portion 30, withdraws said plunger and permits said spring, through the lever 48, to adjust the driving elements out of driving relationship with said belt pulley, and the brake shoe 115 50 in contact with the cam portion 57'.

Having referred to so much of the common mechanism as is deemed important, the improved means for automatically arresting the action of the feeding mechanism between the successive hemstitch figures will now be described.

In the present development of the invention, the arm plate 58 is provided with the tubular bearing 59 into which is mounted a 130

rock shaft 60 provided at its opposite ends with complementary crank arms 61 and 62, said rock shaft being connected, by the crank arm 63 and connection 64, to a second 5 rock shaft 65 which is mounted in a tubular bearing formed in the bracket 66 secured by screws 67, 67 to the cover plate 68. The rock shaft 65 is provided at its outer end with a forked lever 69 which, at times, acts upon 10 the head 70 of the plunger 17 to withdraw the roller 18 from the cam groove 10 formed in the cam 9, in opposition to the spring 19.

In a suitable bearing formed in the forward end of the lever 48, and at one side 15 of the slot 47, is secured, by a nut 71, an oscillating bracket 72 into which is threaded a tubular bushing 73. The bushing 73, which is held in the desired adjustment by a nut 74, acts to guide the lower end of 20 a connection 75 depending from the crank arm 62 and, at times, moves said connection in the direction of its length by contacting with its enlarged portion 76.

When in the operation of the machine the 25 stitching of the seam has been completed, and it is desired to direct the feed of the material at an angle to such seam, the manual control of power transmission is discontinued and the spring 57 permitted to move 30 the lever 48 so as to position the free end of the stop lever 56 in contact with the plunger 38, in which adjustment the parts remain until released by the withdrawal of 35 said plunger, such adjustment of the plunger taking place when the cam portion 57' occupies a position substantially opposite to that shown in Fig. 1, the brake disk continuing its rotation until the said cam portion coacts with the brake shoe 50 to arrest 40 the action of the machine.

Immediately upon the withdrawal of the plunger 38, and before the machine has been brought to rest, the movement of the lever 48, through the connections previously 45 pointed out, causes the forked lever 69 to withdraw the roller 18 from engagement with the cam groove 10. Such disengagement of the cam roller from the cam groove occurs at substantially the time when said 50 roller is about to enter the cam section 11, so that during the continued rotation of the cam portion 57' from the position which it occupies when the plunger 38 is withdrawn, to its position in contact with the brake shoe 55 50, the cam disk 9 is advanced by the momentum of the machine sufficiently to bring the roller 18 in alignment with the surface 77 forming the outer guide wall of the cam section 11, and as the stop-motion mechanism 60 is again manually manipulated to start the machine, the forked lever 69 is caused to release its control of the plunger 17, thus permitting the roller 18 to ride the surface 77 until it is again positioned by the spring 65 19 in the cam groove 10.

From the foregoing it will be understood that when the action of the stitch-forming and cloth-feeding mechanism is interrupted by the action of the stop-motion mechanism, the roller 18 is placed out of engagement 70 with the cam section 11 of the cam groove 10 and retained in such position until after said cam section has passed beyond the field of engagement with said roller, so that when the machine is again started, the formation 75 of a hemstitch figure is repeated without bringing the feeding mechanism into action, and the manual turning of the material at such time causes the stitches first formed after starting the machine to be placed about a given axis. Such manipulation of the stop-motion mechanism to arrest the action of the machine can be repeated any desired number of times between the successive hemstitch figures, making it convenient for the 80 operator to place any desired number of stitches without bringing the feeding mechanism into action.

The construction and operative relationship of the connections 78 and 79, rock lever 80, gear 81, hand crank shaft 82 and bracket 83 have not been specifically defined herein, as such elements are important only in connection with illustrating sufficient of the mechanism of a crank hemstitch embroidering machine to demonstrate the application 95 of the invention.

Claims:

1. In a crank-hemstitch embroidering machine including a stop mechanism for arresting the action of said machine, a stitch-forming mechanism, a cloth-feeding mechanism including a cam-follower and connections between the latter and said stop mechanism for rendering said cam-follower ineffective 100 and allow said stitch-forming mechanism to be operated until arrested by said stop mechanism.

2. In a crank-hemstitch embroidering machine including a stop mechanism for arresting the action of said machine, a stitch-forming mechanism and a cloth-feeding mechanism, the latter comprising a feed-cam, a cam-follower and feed connections for transmitting feed movements to the fabric being acted on, and connections between said stop mechanism and said cam-follower for discontinuing the effective action of said feed-cam and allow said stitch-forming mechanism to be operated until arrested by 110 said stop mechanism.

3. In a crank-hemstitch embroidering machine including a stop mechanism for arresting the action of said machine, a manually operated device to control said stop mechanism, and connections between the latter and, an element of the feeding mechanism of said machine, including a crank-shaft, to move said element out of contact with its coacting member to discontinue the feeding operation 125 130

- and allow the stitch-forming mechanism to be operated independently of the feed until said stop mechanism finally arrests the action of said machine.
5. 4. In a crank-hemstitch embroidering machine including a stop mechanism for arresting the action of said machine, a stitch-forming mechanism and a cloth-feeding mechanism, the latter including a feed-cam, 10 feed-cam follower and feed connections for transmitting feed movements to the fabric being acted on, and means connected with said stop mechanism for discontinuing the effective relationship of said feed-cam and 15 feed-cam follower and allow said stitch-forming mechanism to be operated until arrested by said stop mechanism.
5. In a crank hemstitch embroidering machine including a stop mechanism for arresting the action of said machine, a manually 20 operated device to control said stop mechanism, and connections between the latter and an element of the feeding mechanism of said machine, including an oscillating member 25 carried by said stop mechanism and a rock-shaft mounted upon a stationary part of said machine, to move said element out of contact with its coacting member to discontinue the feeding operation and allow the 30 stitch-forming mechanism to be operated independently of the feed until said stop mechanism finally arrests the action of said machine.
6. In a crank hemstitch embroidering machine, including a stop mechanism for arresting the action of said machine, a manually operated device to control said stop mechanism, and connections between the latter and a yieldingly mounted element of the feeding mechanism of said machine, including an oscillating member carried by said 35 stop mechanism and rock-shafts mounted upon a stationary part of said machine, to move said element out of contact with its coacting member to discontinue the feeding operation and allow the stitch-forming mechanism to be operated independently of the feed until said stop mechanism finally arrests the action of said machine.
7. In an embroidering machine, the combination with a hand-crank feed-directing mechanism, a stop mechanism for arresting the action of the machine, a stitch-forming mechanism, a cloth-feeding mechanism and connections between the latter and said stop mechanism for rendering said feeding mechanism ineffective and permit said stitch-forming mechanism to superpose the stitches at the will of the operator.

In testimony whereof, I have signed my name to this specification, in the presence of two subscribing witnesses.

DONALD NOBLE.
